UNITED STATES PATENT OFFICE.

CHARLES H. DESAUTELS, OF SPRINGFIELD, MASSACHUSETTS, ASSIGNOR TO THE FISK RUBBER COMPANY, OF CHICOOPEE FALLS, MASSACHUSETTS, A CORPORATION OF MASSACHUSETTS.

HEATER CONNECTION.

Application filed June 30, 1922. Serial No. 571,934.

To all whom it may concern:

Be it known that I, CHARLES H. DESAUTELS, a citizen of the United States of America, residing at Springfield, in the county of Hampden and State of Massachusetts, have invented certain new and useful Improvements in Heater Connections, of which the following is a specification.

My present invention relates to connections especially adapted for use in connection with heaters in which cord tires are customarily vulcanized. It has for its object the improvement in various particulars which will more fully appear below of the connections which supply air, water, or steam to the inside of the tires to compress them against the vulcanizing molds, especially in regard to the qualities of reliability, durability, and speed in operation. The invention will now be described in reference to the accompanying drawings, in which

Fig. 1 is a sectional view of a heater with a stack of molds therein, illustrating the manner of attachment of my improved connectors;

Fig. 2 is a detail of one of the connectors;

Fig. 3 is a sectional view of one end of the connectors;

Fig. 4 is an end view thereof;

Fig. 5 is a sectional view of the other end of the connector;

Fig. 6 is an end view thereof; and

Fig. 7 is a fragmentary view, partly in section, of one end of the connector, showing a modified construction.

The heater illustrated in Fig. 1 is of the usual type, having a casing 10 provided with a detachable cover 11 and a hydraulic ram 12, by which a stack of molds 13 can be forced against the cover and thus held closed. Inside the tire 14 in each mold is an expandable bag 15 adapted to be connected to a suitable source of fluid under pressure whereby the tire will be stretched out against the mold. Each bag has a suitable stem 16 to which is joined a connector 17 attached at its other end to a manifold 18, conveniently made sectional, and connected to a source of fluid under pressure by a pipe 19 having a flexible coil 20 to prevent breakage.

It is to the connection 17 that my invention particularly relates. It has been proposed to form this out of a coiled piece of flexible copper tubing, but much difficulty

has resulted from the tubing cracking where it is joined to the necessary union for coupling it to the bag. Furthermore this tubing becomes bent and twisted out of position so that it is difficult to connect and liable to breakage. According to the preferred form of the invention I employ a copper tube 21 surrounded by a flexible metal hose 22 of standard construction. According to the modification illustrated in Fig. 7 this hose is replaced by a spiral spring 23. Returning to the preferred form of Figs. 3 and 5, the connection is preferably constructed so that the hose 22 is substantially fluid tight, so that if the tubing breaks the hose will prevent such rapid leakage of the fluid as would cause damage to the tires in the heater.

A convenient and preferred way of forming the end attachment is by brazing the tubing inside and the hose outside of the shank 24 of a nipple 25 permanently connected at 26 to the manifold 18, and of a nipple 26' at the other end of the connector. A wing nut 27 has a flange 28 held by a flange on the head of this latter nipple, and is provided with internal threads 29 whereby it may be screwed upon the stem of the valve. The nipple has a tapered head 30 so that as it is drawn towards the stem by the screwing up of the wing nut a tight connection will be made.

The hose has preferably a sufficient natural springiness to cause it to tend to straighten, and is bent into a circle (Fig. 2) and its ends clipped by a ring 31 or an equivalent device, fitting loosely enough to permit slippage. By this construction a flexible connector is provided with the wing nut 27 always in position to be connected to the stem of the bag, and the result is attained simply. This latter feature may be used without the double tube if desired.

Having thus described my invention, I claim:

A connector for use in cord tire heaters comprising a manifold, an elastic flexible tube secured thereto, said tube being bent upon itself, and a ring through which each end of the tube passes, whereby the end of the tube not secured to the manifold is held constantly in convenient position for connection to the stem of a tire vulcanizing bag.

CHARLES H. DESAUTELS.
